LONG DAVENPORT BED

Joseph R. Thomas, Chicago, Ill.

Application August 17, 1953, Serial No. 374,669

4 Claims. (Cl. 5—28)

This invention relates in general to davenport beds and is more particularly described as a long davenport bed in which the folding sections are spaced inwardly from both of the arms of the bed to provide a plurality of sections which extend outwardly in front of the bed when it is extended so that a person lies at right angles to the davenport seat rather than parallel thereto in the conventional long bed type.

In general, there are two types of bed davenports; the so-called short bed in which the sections are mounted between the end pieces and unfold forwardly in alignment in front of the bed so that a person sleeps at right angles to the seat, and the long bed in which a single bed section is folded outwardly from the seat section and a bed of substantially full width is formed so that a person sleeps parallel with the seat section. This conventional long seat bed is objectionable as it is difficult to provide a convertible sleeping surface to provide sufficient space for holding the mattress and bed clothes therein when the bed is folded, and if two persons are using the bed, one is substantially enclosed by the back and arms of the seat.

The present invention provides a conventional multiple section folding bed structure in connection with a long davenport frame and in providing a filler for each side of the seat section within the frame to occupy the space between the foldable seat section of the bed and the supporting arms at the sides of the bed.

An important object of the invention is to provide a filler construction for a folding davenport bed which becomes a part of the seat when the structure is used as a davenport to occupy the space at each side of the folding seat structure which is not required when it is unfolded to form a bed.

A further object of the invention is to provide an extension of the seat structure at the ends of a davenport bed which are not overturned with the folding bed structure when it is inverted to form a bed.

A still further object of the invention is to provide a resiliently supported filler at the ends of a folding bed structure which together form a continuation of a seat surface longer than the width of the folding bed structure.

Other objects of the invention will appear in the specification and will be more apparent from the accompanying drawings in which,

Fig. 1 is a plan view of a long davenport frame from which an outwardly folding bed structure is unfolded into bed position with extensions within the frame at the ends of the seat structure in accordance with this invention.

Fig. 2 is a front elevation of one end of a davenport as shown in Fig. 1 showing the parts in the folded or seat position.

Fig. 3 is an enlarged view of one end of the structure as shown in Fig. 1.

Fig. 4 is a perspective view of the filler and a portion of the folding mechanism at one end of the davenport showing a portion of the supporting frame in a partially elevated position; and

2

Fig. 5 is a sectional view as taken on the line 5—5 of Fig. 3.

An ordinary short davenport is sometimes known as a love seat, and it is distinguished from the long davenport bed in which the seat is usually of sufficient length so that a person may lie down upon the seat parallel to the back thereof. A folding bed structure of full width is ordinarily about 64" in width and fits closely between the ends or arms of the structure so that it may fold and unfold closely therebetween, as shown more particularly in my Patent No. 2,755,486 of July 24, 1956, but if this construction is applied to an ordinary long type of davenport bed in which the distance between the insides of the end arms is 72", there is a space of about 8" between this folding bed structure and the insides of the arms. By dividing this space into two sections of 4" each at each side of the folding bed, which requires a support for loose cushions when the davenport is used as a seat, the present invention provides a resilient filler which forms an extension of the seat section at each end, and provides a support at each side of the bed sections when they are extended to form a bed. The filler may be at both sides of the folding bed as shown in Fig. 1 or at either side thereof as represented by Fig. 3 depending upon the relative length of the davenport frame and the width of the bed frame and to suitably fill up the space between the side arm 16.

Referring now more particularly to the drawings, a long davenport bed comprises a frame 10 for supporting a back 12 which may be fixed or movable and end frames 14 for arms 16. Extending between the front ends of the frames 14 at the lower ends of the arms 16 is a movable front board 18 which closes the space between the end frames and provides an enclosure for housing the connected sections 20, 22 and 24 of a folding bed frame which is mounted in the davenport frame.

The folding bed frame may be of any conventional form but preferably is provided with a mounting for the seat section 20 which is invertible in the davenport frame and comprises a mounting bar 26 fixed to a supporting panel 25 spaced inwardly from the end frame 14 in a forwardly inclined position with a link 28 pivoted at the rear of the mounting bar 26 and a link 30 pivoted at the front end of the mounting bar. The upper ends of these links 28 and 30 are connected at opposite ends of a supporting bar 38 so that this bar may be inverted from a lower or seat position in contact with a bracket 34 secured intermediate the ends of the mounting lever 26 to a bed position in which the forward link engages a bracket 36 projecting inwardly from the bed end 10 in the path of the link for supporting it and the bar 32 in a bed position.

The seat section 20 supported by the bar 38 is inverted from seat position to bed position in a well known manner and as also clearly shown in my Patent No. 2,755,486. The front board 18 is rigidly connected to the front of the bar 38 and it is moved upwardly and rearwardly from its position between the end frames 14 to a position as indicated in Fig. 4 in changing the folding structure from a seat to a bed, the bed sections folding downwardly into alignment, and the front board then extending in a fixed position in front of the back 12.

At the front of each panel 25 is a front board 40 which extends from the panel to the end frame 14 but is spaced rearwardly from the front of the end frame a distance substantially the thickness of the front board 18 so that when the bed structure is folded, within the davenport frame, the front board 18 will be located in front of the front piece 40 at each end to cover and enclose them and to complete the space between the front surface of the side arms to provide a smooth and unbroken surface.

In the space between the panel 25 and the end frame

14 at each end, a space is thus provided for receiving a resilient seat extension which preferably comprises a plurality of flexible straps 42 connected at the ends to plates 44. The filler may also comprise spring coils or resilient pads to fit in the space between the end frame 14 and the panel 25. The forward plate 44 is connected by links 46 to a bracket 48 in the form of an angle bar, one web of which is secured to the front piece 40. At the rear end, the plate 44 is connected by helical springs 50 with a bracket 52 in the form of an angle bar and is secured to a portion of the supporting frame 10. Thus the straps 42 are resiliently mounted and supported and they are located substantially at the level of the seat fabric when the folding bed sections are in seat position so that the straps form a substantial continuation of the seat surface in line therewith and are resilient or yielding similar to the seat section and extending up close to the ends 14 so that when a loose cushion 54 is placed on top of the seat section in the seat position as shown in Fig. 2, there will be no hard or unyielding support at the end of the cushion close to the inside of the arm 16.

In order to suitably finish the top of each filler section, a resilient fabric cover 56 may be applied over the straps 42 and their end connections, and one end of the cover is secured by upholstery tacks 58 to the top of the front piece 40 and the rear of the cover is secured to an upright portion of the frame 10 by upholstery tacks 58 or other suitable means.

With this construction, it is apparent that a full size folding bed of any desired construction may be suitably connected in a long davenport bed frame by adding fillers at the sides of the bed section which is normally attached in the frame and in operating the folding bed in a normal manner swinging it into and out of the frame to provide a sleeping surface at right angles to the back of the davenport rather than parallel thereto. The exact structure of the folding bed is generally independent of the long bed structure, but as herein described, a folding bed section which is invertibly mounted in the frame particularly cooperates with a davenport frame in which a front board is movably mounted between the front portions of the end frames. In order to additionally strengthen the forwardly projecting end frames, it is customary to provide an angle brace 60 which extends downwardly in the form of a yoke below the bottom of the panels 25, but with upwardly bent end pieces which are secured to the sides of the panel in a well known manner.

While a preferred construction has been described in some detail, it should be regarded as an illustration or an example rather than as a limitation or restriction of the invention, since various changes in the construction, combination, and arrangement of the parts may be made without departing from the spirit and scope of the invention.

I claim:

1. The combination with a davenport bed having a

supporting seat frame and spaced arms at the ends, of a folding bed comprising a plurality of pivotally connected sections, the width of the folding bed being less than the length of the seat between the arms, means forming a hollow filler for at least one end of the frame attached to the inside of the arm, mounting means for the folding bed attached to the inside of the filler for mounting at least one of the connected sections for overturning movement in the frame so that the bed sections will swing outwardly from the davenport frame to form a bed extending at right angles to the frame and will swing inwardly to form a seat, resilient straps connected at their front and rear ends in the filler and located at the level of the folding bed sections when they are folded to form a seat, the filler being inset from the outer end of the arms and the davenport frame including a front board which is connected to one of the said overturning bed sections to swing upwardly from the space at the front of the frame and to be carried by the bed section to one end of the bed when it is moved into extended position.

2. In a folding davenport bed in accordance with claim 1, the folding bed including one section mounted for overturning movement in the davenport frame and the front board being connected to said overturning section and movable therewith to the rear of the bed adjacent the back of the davenport when the folding bed is extended in front of the davenport frame to form a bed.

3. In a folding davenport bed in accordance with claim 2, means connecting the filler frames below the seat and the front board extending between the arms and in front of the hollow filler frames.

4. In a folding davenport bed in accordance with claim 1, the straps being connected by links to the front end of the hollow frame and by spiral springs at the other end of the hollow frame and a fabric cover secured to the hollow frame and extending over the resilient straps and the mounting means at the ends thereof, the cover forming a continuation of the seat, when the bed sections are folded within the bed and forming a resilient support adjacent the bed surface when the sections are extended to form a bed.
